UNITED STATES PATENT OFFICE

GEORGE WOELFEL, OF YERKES, PENNSYLVANIA

MACHINE FOR SOAPING HEAVY WOOLEN FABRICS

Application filed April 2, 1929. Serial No. 351,866.

This invention relates to a mechanism and device for assisting the operator of said machine in manually lifting and drawing the heavy slippery soap-filled goods from said machine; to remove from the goods a substantial quantity of liquid soap and to leave therein a quantity of liquid soap sufficient to remove the soil in the goods during the next subsequent step in the process of cleansing the same, without subjecting the fibers thereof to any substantial pulling or stretching operation, or to any attrition which tends to cause the fibers to felt and the goods to shrink.

The apparatus constituting the present invention is, in many details, fully shown and described in Letters Patent of the United States, No. 1,711,162, granted to me April 30, 1929, and the present application constitutes a continuation in part of the application upon which issued said Letters Patent and which was copending at the time when the present application was filed.

One of the objects of the present invention is to provide a soaping machine, with means controlled by the foot of the operator, for assisting the operator to draw, with his hands, the heavy slippery soap-filled goods from a liquid soap bath without stretching or tearing the fabric and to simultaneously express therefrom some of the liquid soap contained therein but leaving in the goods enough liquid soap to hold the particles of soiled solid matter in suspension in the soap contained in the goods.

A further object of my invention is to provide a soaping machine with a pair of rollers between which the goods may be drawn by the operator in removing the goods from the bath of soap, one of said rollers being mounted in a fixed relation with respect to the soaping machine and the other being yieldingly held out of contact or engagement with said first-mentioned roller and yieldingly held by the foot of the operator against the top surface of the goods drawn between the rollers to express from the goods a substantial portion of the liquid soap contained therein and leave in the goods a sufficient amount of soap to hold the solid particles loosened from the

fibers by the soap in suspension in said liquid soap.

A further object of my invention is to so mount one of the rollers of a pair of rollers, through which the goods are drawn in removing the same from the soaping machine, in yielding bearings which will permit the roller to rise and fall with respect to the other roller and to the goods passing between said rollers and to move into position in which the axis of the roller is not parallel to the axis of the other roller in order that said first-mentioned roller may tip and slant and conform to different thicknesses of material passing between the rollers simultaneously.

A further object of my invention is to provide a soaping machine with a roller, power driven, and provided with a relatively smooth surface and with a coacting roller, the position of which is controlled by the foot of the operator and movable toward and away from said first mentioned roller whereby any excessive pull on the goods being removed from the soaping machine may be prevented by the operator and any wear on or stretch of the goods is prevented.

A further object is to provide a device giving the operator standing in front of the trough, free and unmolested access to the inner casing, and to the rear sides of the rollers, by reaching over the trough and rollers into the casing, whereby an end of the soaped goods may be grasped and easily placed between the rollers which are normally maintained rather widely separated.

Other objects of my invention will appear in the specification and claims below.

In the drawings forming a part of this specification and in which the same parts are designated by the same reference characters throughout the various views,

Fig. 1 is an end elevational view of the soaping machine with my improvements.

Fig. 2 is a vertical cross-sectional view through the machine shown in Fig. 1.

Fig. 3 is a front elevational view of the machine equipped with my improvements.

Fig. 4 is a fragmentary plan view of one end of the trough for returning the soap which is expressed from the goods back into

the soaping machine and clearly shown on an enlarged scale the mounting for the upper roller.

Fig. 5 is a vertical sectional view on the same scale as that of Fig. 4, showing the manner of mounting the rollers and the connections therefor for positioning the upper roller with respect to the lower roller during the operation of the mechanism.

Fig. 6 is an elevational view of the bearing bracket and resilient guide rod, looking in the direction of the arrow shown in Fig. 5.

In order that the purpose and advantages of the present invention may be manifest, I will briefly describe my process of cleaning heavy woolen fabrics without subjecting the fibers to attrition and without causing the goods to shrink.

When one attempts to remove from a heavy woolen fabric, such as a blanket, dirt or soil by the use of attrition or rubbing in the presence of soapy water, the adhesion of the dirt and soil to the fibers is not completely or sufficiently broken, with the result that the dirt is distributed over a larger area but is not actually removed and still clings and adheres to the fibers. The rubbing of the woolen fibers over each other in the presence of warm soapy water results in a shrinking of the fabric which is very undesirable.

I have discovered that if such goods be subjected to a very strong soap solution, that is to say, a strong liquid soap, and preferably containing an alkali, such as washing soda, the adhesion of the dirt to the fibers is broken and that the dirt having been thus loosened or freed from the fibers does not become re-attached thereto so long as the solid matter and the fibers are covered with soluble soap. The solid matter so freed from the fibers appears to be held or retained in suspension in the soap, and when a woolen fabric so filled with strong liquid soap is subsequently rinsed, then the solid matter or dirt suspended in the soap is floated off or carried away with the soap, leaving the fabric extremely clean.

But in carrying out this process, care must be exercised to avoid and eliminate all vigorous or violent rubbing or agitation of the goods. The fabric should be filled with the liquid soap, by gently slowly moving the goods through a relatively large bath of liquid soap and then gently lifting the goods from the bath and then immersing them in it without subjecting the fibers to any substantial attrition, and in the subsequent steps of removing the soap and soil in the soap from the goods, the same gentle treatment of repeated immersion and lifting of the goods out of a bath of water should be performed without rubbing or pulling the fibers.

In carrying out my invention, I preferably

use a soaping machine A, which may, in general construction, be a rotary hydraulic of a conventional type of construction and I substantially half fill said machine A with about fifty (50) gallons of warm liquid soap, preferably containing washing soda. I prepare the soap for this soap bath by boiling a good quality of tallow soap in water, the proportion being substantially five (5) pounds of the soap to substantially fifty (50) gallons of water. An alkaline test of the soap produced will show substantially 2% alkali, Bé. The temperature of the soap in said machine is maintained at substantially 105° F. The quantity of soap thus used is several times greater than that which is generally used in the ordinary washing of woolen goods in soapy water and the strength of the soap is two or three times stronger than that required in process for washing blankets in soapy water.

After having been placed in the machine A, the machine is slowly rotated thereby lifting the goods from and dipping them into the bath of soap for a period of from one and a half to two minutes. If the soil is not loosened from the fibers within this short time, the dirt or stain cannot be removed thereby even if allowed to stay for a longer period.

The first step of my improved process is not a washing; it is a soaping step by which woolen goods are thoroughly filled with liquid soap. The strong liquid soap dissolves the adhesive substance by means of which the solid particles of dirt are attached to the fibers. When these solid particles are once removed they are held in suspension in the liquid soap, and if the liquid soap containing these particles of dirt be hereafter passed back and forth and therefore through the soaped fabric, the said particles will not adhere to the slippery fibers but will be held in the soap and will float out of the fabric as the soap is removed from the fabric.

The soaping machine A preferably comprises an inner perforated or foraminous cylinder 1, journaled coaxially within an outer cylinder or casing 2, the ends of which are closed by the heads 1', 1'. I prefer to divide the inner cylinder 1 into two like compartments 3 and 4 respectively by a perforated partition 5 extending diametrically across and for the full length of the rotating cylinder 1 and I provide the periphery of the inner cylinder 1 with a suitable door or closure 6 giving access to both of the compartments (3 and 4) in the inner cylinder 1 and formed by the partition 5. This door or closure 6 may be tightly held in place to close the cylinder in any suitable manner. The cylindrical surface of the casing 1, the partition 5 and the closure 6 are preferably provided with perforations 7.

In each compartment I preferably place a pair of blankets, thus treating two pairs of

blankets at once in the machine. The cylinder 1 is then rotated at a rather slow speed for the very short time of one and a half to two minutes, in which time the blankets will 5 become thoroughly filled with the liquid soap. The operation of the cylinder is then stopped and the soap-filled blankets are then removed and placed upon a support. Two more pairs are similarly placed in the cylinder 10 and similarly gently soaped for a minute and a half or two minutes. The machine is then stopped and the soaped blankets are removed. This soaping of the soiled goods 15 for the very short time above indicated constitutes the first step of my improved process of cleansing blankets forming the subject-matter of my copending application, Serial Number 204,708, filed July 11, 1927.

Because the perforated partition merely 20 divides the rotating cylinder into two compartments, the fibers of the goods are not subjected to any substantial attrition or agitation or rubbing action during the rotation of the cylinder. The blankets do not completely 25 fill the compartments; they slowly easily slide as the partition tilts in rotating with the cylinder but are not pulled or squeezed or rubbed by said rotation. The substantial 30 action to which they are subjected is one of alternating gently dipping or immersing the blankets in and moving them through the warm liquid soap, then just as gently lifting them out of the soap, allowing the soap solution to run out of them back into the bath through which the blankets have 35 passed, with the result that the soiled fibers of the blanket are thoroughly covered with slippery undecomposed liquid soap which prevents the readhering thereto of the dirt held in suspension in the soap. The fibers 40 are not rubbed over each other. There is no matting or felting of the fibers and consequently, no shrinkage of the goods.

The next step of my improved process is 45 that of removing the blankets from the soaping machine A, and it is to this step that the present invention particularly relates. When the rotation of the inner cylinder 1 is stopped, with the door or closure 6 in registration 50 with the opening 8 in the outer cylinder 2 and the removal of said closure 6 gives the operator access to the blankets in both compartments 3 and 4 of the inner cylinder 1.

The operator, with his hands, proceeds to 55 draw out of the compartment 3 and end of one pair of blankets. The blankets are now heavy with soap and slippery. It is not easy to lift the blanket out of the cylinder, nor is it desirable to waste all of the soap which is contained 60 in the blanket. I therefore provide the soaping machine A with a trough-like structure 9 mounted on the outside of the outer casing or cylinder 2 and having the top edges thereof substantially in the horizontal plane 65 of the lower edge 8' of the opening 8 in the

cylinder 2. This trough-like structure 9 projects outwardly from the surface of the cylinder 2 only a few inches and is of a depth sufficient within which to mount a long roller 10 approximately 2½ inches in diameter and terminating at each end rather close to the inner sides of the side walls 11 of the tank. The roller 10 should be a little longer than the length of the opening 12 in the inner rotary cylinder 1 and through which the 70 goods are drawn out.

The roller 10 is preferably mounted rigidly on a shaft 13, the ends of which are journaled in bearings or boxes 14, 14, which freely rotates in said bearings. The highest point in 80 the periphery of the lower roller 10 is preferably at or about level with the top edge of the trough 9.

Above this roller 10 I preferably mount a second roller 15 of substantially the same 85 diameter as the roller 10 and in such a way that each end thereof is movable vertically toward and away from the lower roller 10. I, therefore, mount on the upper edges of the side walls 11 of the tank 9 a bracket 16, one 90 on each wall, said bracket comprising a journal bearing 17 in which rotates the shaft 18 on which the upper roller 15 is rigidly mounted to turn therewith. From the bearing portion 17, the bracket 16 extends outwardly 95 away from the cylinder 2 of the soaping machine.

This bracket 16 is preferably strong and stiff and is provided with marginal ribs or flanges 19 extending outwardly from the edges thereof throughout the entire length of the bracket. The front end 16' of the bracket 16 is arranged to normally rest on the upper edge of the side wall 11 and near said end 16' the bracket is provided with a hole 20 elongated in the direction of the length of the bracket. Through this opening or hole 20 passes a screw 21 rigidly attached to the side wall 11. Preferably, the head of this screw is flattened or elongated so that the long dimension thereof is greater than the width of the spaces between the ribs or flanges 19, but the short dimension is less than the distance between the ribs 19 of the bracket so that when the long dimension of the head 22 is 110 lengthwise of the bracket arm, the front end 16' of the bracket is rather loosely attached to the trough 9 and may be lifted vertically a distance substantially equal to the height of the ribs 19.

Between the elongated opening 20 and the journal bearing 17, the bracket 16 is provided with another hole 23 adapted to receive the upper threaded end 24 of the rod 25. After the upper end of the rod 25 has been pushed upwardly through the hole 23, a washer 26 may be slipped over the rod and then a nut 120 may be threaded over the upper end 24, as clearly shown in Fig. 6. There are two of these rods 25, one on each side of the machine, 125

one for each bracket 16 and they pass through holes 28, 28 extending substantially vertically through the side walls 11 of the trough 9. These holes are preferably elongated in a direction toward and away from the cylinder 2, and the smaller dimension thereof should be a little greater than the diameter of the rods 25. The upper ends 28' of the holes 28 may also be elongated in a direction toward and away from the casing 2, but the said upper ends are of larger diameter than the lower portion of the hole 28 to provide a shoulder 29 in the hole for seating the lower end of a stiff spiral spring 30 and a washer 30' and to provide space above said shoulder for the reception of the spring 30. The elongation of the hole 28 is to permit of a slight back and forward travel of the rods 25 due to the arcuate path of the movement of the roller 15 toward and away from the roller 10.

The spiral springs 30 each surround a rod 25 respectively, and their upper ends press against the under surface of the bracket 16 thus normally holding the journal 17 of the bracket 16 and roller 15 carried thereby in their uppermost position with the upper surface of the bracket 16 pressed firmly against the under surface of the washer 26 under the nut 27, and against the head of the screw 22. The front end 16' of the bracket 16 is thus the only portion of the bracket 16 which normally may rest against the upper edge of the side walls 11. These substantially vertical rods 25 pass loosely through the openings 28 in the side walls 11 and extend downwardly to a point a little above the floor where they are connected together by a stiff transverse bar 31 which may be integral with the rods 25.

This transverse bar 31 is preferably rotatably secured to the under side of a pedal 32, as by staples 33. The pedal 32 extends outwardly to a position where the free end thereof is accessible to the operator standing in front of the trough 9, and the rear end of the pedal is suitably pivotally or hingedly connected to some rigid support as, for instance, a bracket 34 mounted on the under side of the outer casing 2 of the soaping machine.

The pedal 32 may be operated, as in my said copending application, by the operator's foot placed upon the upper surface of the pedal. I may, however, hang from the front end of the pedal 32 a flexible strap providing a stirrup 32' in which the operator may place his foot in order to depress the said lever to bring the roller 15 into a position below its normal elevated one.

The upper roller 15 may be provided with longitudinally depressed flutes or ridges 35. The outer end of the shaft 13 on which the lower end of the roller 10 is mounted, may be provided with a pulley 36 over which runs a belt 37 driven from any suitable source of

power as, for instance, an electric motor 38 indicated in Fig. 1, having a drive pulley 38'.

Since it is necessary for the operator to have free access to both sides of the roller, I arrange the belt 37 to run downwardly from the pulley 36 so as to leave a clear space between the rollers 10 and 15 and the outer cylinder 2, and a clear space above the roller 15. I, therefore, have shown the belt 37 as running under idlers 39 mounted on the side of the outer casing 2 of the soaping machine A.

It is to be understood that any suitable mechanism may be employed for imparting to the lower roller 10 a continuous motion in such a direction as to make the upper surface of the roller 10 travel away from the opening 8 of the outer casing 2 of the soaping machine A.

This roller mechanism last above described, constitutes a mechanism whereby to assist the operator in withdrawing the heavy slippery soap-filled goods from the interior of the soaping machine A, and it provides, at the same time, a means to remove from the goods any excess of liquid soap which is not needed in the next or subsequent step of the process.

In the practice of my invention, all the soap not needed for the extraction or removal of the dirt from the goods, is extracted or expressed from the goods. Only enough is left in the goods to keep whatever dirt remains in the goods in suspension in the liquid soap.

To remove the goods from the rotary cylinder 1, the operator passes his arms over the roller 15 into the inner cylinder 1, and finding an end or a part which he can grasp despite the slippery condition of the goods, he draws that portion upwardly into a position between the rollers 10, 15, the upper roller being held separated from and above the lower roller 10 by the tension spring 30. He now presses downwardly on the pedal 32 with one foot, placing his foot either on the top side of the pedal 32, or putting his foot into the stirrup 32', the latter giving him a little more lateral freedom when he is obliged to work at one or the other ends of the machine. The downward movement of the pedal 32 brings the upper fluted roller 15 down against the upper surface of the goods now between the rollers 10, 15, but the operator continues to manually draw the goods between the rollers outwardly from the casing. The lower roller is slowly driven by the motor 35 in a direction to assist in drawing the goods out of the soaping machine. The upper roller 10 is but a presser roller and the operator may readily vary the pressure of his foot on the pedal 32 and permit of the application of only as much pressure on the upper surface of the goods as he needs to assist him in gently drawing the goods out of the soaping machine.

The goods come out of the soaping machine in varying thicknesses depending upon the way in which they may lie in the machine. The thickness of the goods at one end of the 5 roller may be much greater than that at the other end of the roller. The operator by varying the position of his pedal, may permit the upper roller to rise and fall to follow the upper surface of the goods passing between 10 the rollers, without jamming the mechanism or breaking the roller, or substantially squeezing the goods. Although the shaft 18 of the upper roller 15 is journaled to rotate in the bearing 17, the bracket 16 is not rigidly 15 mounted or secured to the trough. It may rock slightly transversely, so that the axis of the shaft 18 may make a positive angle to the axis of the shaft 13, and, as fast as the operator removes the pressure of his foot from 20 the pedal 32, just so fast does the spring 30 force the upper roller 15 upwardly away from the roller 10.

The rollers 10, 15 are substantially longer than the length of the opening 12 in the rotary cylinder 2 in order that the goods shall 25 always come out of the machine between the rollers and not be caught and wrapped around the end of the rollers, for this would tear, stretch and possibly ruin the goods.

In order to further insure that the goods 30 may never extend beyond the ends of the rollers 10 and 15, I mount a pair of guard or protector plates 40 between the ends of the said rollers and the inner sides of the side 35 walls 11 of the trough. These guard plates are provided with a pair of substantially aligned slots 41 and 42, the lower slot 41 being of a width greater than the diameter of the shaft 13, so that the guard may be slipped 40 down over the end of the shaft to the upper end of the slot 41, the upper slot 42 being adapted to loosely receive the upper shaft 18. The upper slot 42 may be considerably 45 longer than the lower slot so as to permit the upper shaft 13 to rise and fall during the operation of the machine without rising out of the slot 42. The length of the upper slot 42 is greater than the vertical travel of the upper shaft 13 as raised and lowered by the foot 50 pedal and spring. The forward edges of each plate 40, that is to say, the edges nearest the cylinder of the soaping machine A, are preferably provided with inwardly extending flanges 43 to guide and hold the goods away 55 from the ends of the rollers.

The liquid soap which is expressed from the goods and falls into the trough 9 passes through an opening 44 at the bottom of the trough back into the bath of soap within the 60 outer cylinder 2 of the machine. I may provide the outer cylinder 2 with a pipe 45 and a valve therein, for draining the contents of the outer cylinder when desired. In order to maintain the soap at the desired temperature, 65 I preferably provide a live steam pipe 46 and

a coil or radiator 47 lying near the bottom of the outer cylinder and between it and the inner cylinder controlled by a valve 48.

It is to be understood that the liquid soap 70 which I use, becomes thick when cool and practically solidifies so that it is unfit for use in my machine unless the temperature is maintained at substantially 106° F.

The inner cylinder 1 is to be rotated at a low speed and I have shown a shaft 49, upon 75 which said cylinder is mounted to rotate, as being driven by a pair of pulleys 50, 50. With a loose one 51 between them so that by shifting a straight and crossed belt (not shown), I may rotate the cylinder first in one 80 direction and then in the opposite direction. Any suitable mechanism, however, may be employed to rotate the cylinder 1 slowly at which speed the woolen goods will not be particularly agitated or rubbed and the soap 85 will not be violently forced through the goods by centrifugal force and the goods will be gently submerged and as gently lifted out of the bath whereby the soap will thoroughly permeate the goods and the dirt will float 90 away with the soap when the soap is extracted from the goods or dissolved out of them.

I preferably provide the rod 25 with a collar 52 which may be freely slid longitudinally of the rod 25 and held in any fixed or predetermined position by a set screw 52' to limit the upward movement of the roller 15 away from the roller 10 under the influence of the spring 30 in order to prevent the shaft 18 from being forced upwardly above the upper end of the guard plate 40. 95

It will be apparent that if the collar 51 were loosened, the spring would force the shaft 18 upwardly clear to the slot 42 and the guard 40 would swing forwardly on the shaft 13 to an inverted position and then fall into 105 said trough were it not for the lugs 53 on the top edges of said brackets 14 projecting inwardly beyond the plane of the adjacent guard 40.

I also preferably mount, on each side of the trough 9 and between the guards 40, a resilient vertical member 54 against which the edges of the fabrics engage in leaving the soaping machine. This resilient member 54 may comprise a resilient rod, the upper portion 54^a of which is immediately in advance of the rollers 10, 15 and terminates in a smooth loop or eye 54^b upon which the goods will not catch and tear; a forwardly 115 downwardly extending portion 54^c passing between the roller 10 and the casing 2; a coiled portion 54^d to provide resiliency; and a substantially horizontal lower end portion 54^e. The bearing plates 14 may each be provided with a socket 55 having a socket hole into which said horizontal portion 54^e fits and in which it is rigidly held by a set screw 56. The portions 54^a and 54^e are preferably normally inclined toward the middle 120 125 130

of the rollers and they yield toward the ends of the rollers 10, 15 when engaged by the edges of the goods, but the resiliency of these members causes them to press back on the goods and force them toward the center of the rollers thus limiting the extent to which the goods may be spread laterally in passing between the rollers. Any other suitable resilient member or device may be employed, however, without departing from the spirit and scope of my invention.

The smooth driven lower roller 10 is rotated slowly and does not exert very much tractive force upon the slippery blankets or other goods passing between the rollers and therefore, the rollers will not pull or tear or stretch the goods between them. If the upper roller is pressed too heavily against the upper surface of the goods passing therebetween, said roller 10 will slip but will not pull or tear or otherwise injure the fabric. If too little pressure is exerted on the upper roller, a similar slip of the lower roller will occur. Moreover, the lower roller will generally slip over the undersurface of the goods if the operator is not continually drawing the goods manually outwardly between the rollers. These rollers are of assistance to the operator in manually drawing the blankets out of the soaping machine. The function of said rollers is more like that of doctor or scraper rollers which leave a substantial quantity of soap in the goods, than that of wringer rollers, which express as much as possible of the liquid content.

I usually place in the soaping machine about fifty (50) gallons of liquid soap and for economic treatment I preferably treat at one operation two pairs of double blankets or the equivalent of eight single blankets. I preferably leave in each blanket enough soap to thoroughly cleanse the blanket during the next step of the process. After leaving the rollers, two pairs of double blankets, of average weight, may contain nearly ten (10) gallons of liquid soap, or speaking generally, one (1) gallon of liquid soap for each single blanket. It will now be apparent why the soap-filled goods are not required to be subjected to a heavy pressure and why the goods are drawn manually between the rollers and how it is that the goods are not subject to any substantial attrition which would tend to felt the fibers.

The excess soap removed from the goods falls into the trough to be used again in connection with the cleaning or cleansing of the next lot of blankets to be treated in the soaping machine. Communication between the trough 9 and the interior of the outer cylinder is provided by means of the passage 44 (see Fig. 5).

From time to time and preferably after each removal of a lot of goods which have been treated in the soaping machine, enough fresh

liquid soap should be added to compensate for the loss to the soap bath of the soap remaining in the blankets or other fabrics after they leave the rollers 10, 15. The soap remaining in the soaping machine is used over and over again, subject to replenishment, to keep the quantity substantially up to fifty (50) gallons. It is only when the soap is discolored, as by soluble dyes from colored goods that have been treated therein, that care must be taken not to use that discolored soap again for white goods. Except for this consideration, I have found that although the soap may look dark and discolored, it does not give up to the goods being treated therein, so the solid insoluble matter held in suspension therein, but, on the contrary, continues to produce cleaner, lighter, more fluffy and softer washed goods than was obtainable by the practice of the processes heretofore used.

I have found that if goods are allowed to remain in the soap bath for more than two minutes, the soap does not injure the goods nor cause them to shrink, so long as they are not subjected to an agitation or other action of attrition. In using this soaping machine, heavy woolen goods are not perceptibly reduced or shrunk or felted, and the colors are often brightened.

It is not necessary to vary the soap bath in the day's run of work to adapt it to the varying degrees to which the goods received from different sources are soiled. In the practice of my invention this factor does not have to be considered. The same strong soap bath is used on goods soiled to different degrees and all the goods treated are cleansed perfectly irrespective of their condition of soil.

Having thus described my invention, what I claim and desire to protect by Letters Patent of the United States is:

1. A soap expressing device adapted for use in connection with an elongated soaping container having a trough on the side thereof or near the top of said container and provided with a drain to said container, comprising the combination of a driven roller mounted in said trough with its axis parallel to that of said container and with the upper surface thereof substantially level with the top edges of said trough, a presser roller arranged substantially parallel to said driven roller, the space above said rollers being clear to give the operator free access over said rollers into the inside of said soaping container, means to continuously rotate said driven roller so that goods passing between said rollers will be drawn away from said casing, resilient means normally holding said presser roller substantially spaced away from the top of said driven roller, foot operated means to lower said presser roller against the tension of said resilient means into engagement with the upper surfaces of any goods

between said rollers, whereby the motion of said driven roller on the goods between said rollers assists the operator to manually draw the goods between said rollers and said rollers are operative to express liquid soap from said goods without felting the fibres of said goods, and resilient means between said casing and the ends of said rollers to yieldingly press against the edges of said goods to keep the goods away from the ends of said rollers.

2. In a device for expressing soap from heavy woolen goods and adapted for use in connection with an elongated soaping container having a trough on the side thereof near the top of said container and provided with a drain to said container, the combination of a driven roller having a substantially smooth surface, mounted in the upper part of said trough, a pair of brackets on the opposite sides of said trough, each being loosely and pivotally mounted at one end so that the bracket is movable toward and away from said container and vertically with respect to said trough, and each bracket having a bearing at the other end thereof, a presser roller journaled in said bearing above said smooth roller and on an axis substantially parallel thereto, the space above said presser roller being clear to give the operator standing in front of said rollers free access over said presser roller to the rear of said rollers and into the interior of said soaping container, means to rotate said driven roller to assist the operator in drawing the goods outwardly between said rollers, springs normally pressing against said brackets respectively and normally holding said presser roller spaced above said smooth roller, rods loosely connected to said brackets respectively and extending below said trough, a pedal connected to said rods and operable by the foot of the operator standing in front of said trough to hold the presser roller pressed against the upper surface of the goods passing between said rollers.

3. In a soap expressing device adapted for use in connection with an elongated soaping container having a trough on the side thereof near the top of said container and provided with a drain to said container, the combination of a shaft mounted in said trough, a driven roller mounted on said shaft and extending substantially the full length of said trough, and means to continuously rotate said shaft and said roller carried thereby, a pair of complemental brackets, loosely and pivotally mounted at opposite ends of said trough so that said brackets may be moved toward and away from said container and vertically with respect to said trough, bearings in each bracket, a shaft mounted in said bearings, a presser roller mounted on said shaft, springs pressing upwardly on said brackets to normally hold said presser roller spaced from said driven roller, foot operated

means connected to said brackets for drawing said presser roller into engagement with goods passing between said rollers, the said loose pivotal mounting of said brackets providing limited independent movement of each bracket with respect to the other, whereby said presser roller may conform to and rest against the upper surface of the goods drawn between said rollers when the thickness of the goods at the opposite side edges thereof varies, a pair of complemental guard plates, each loosely supported on the end of the shaft of said driven roller and having a slot extending upwardly from the lower edge thereof in which rotates the shaft of the said driven roller and a substantially vertical slot extending downwardly in each plate from the upper edge thereof and in which the shaft of the said presser roller rotates, said plates being each provided with a flange extending inwardly toward the middle of the rollers and positioned between said container and the ends of said rollers to prevent the goods from spreading beyond the ends of said rollers.

4. In a soap expressing device adapted for use in connection with a soaping casing having an opening thereto extending substantially the full length of said casing and a trough mounted on the outside of said casing extending for the full length of said opening, the top of said trough being substantially at the level of the lower edge of said opening, the combination of a shaft mounted in said trough, a driven roller mounted on said shaft and extending for substantially the full length of said trough, means to continuously rotate said shaft and said roller carried thereby, a pair of complemental brackets loosely and pivotally mounted on the opposite end walls of said trough so that said brackets may move toward and away from said casing and also vertically with respect to said trough, a cylindrical bearing in each bracket, a shaft mounted in said bearings, a presser roller mounted on said shaft, springs pressing upwardly against said brackets to normally hold said presser roller spaced from said driven roller, foot operated means connected to said brackets for drawing said presser roller into engagement with goods drawn between said rollers, said loose pivotal mounting of said brackets providing limited independent movement of each bracket with respect to the other bracket, a pair of complemental

guard plates each mounted on the end of the shaft of the driven roller respectively and having a slot extending upwardly from the lower edge thereof in which the shaft of said lower roller turns and a substantially vertical slot extending downwardly from the upper edge thereof in which the shaft of said upper roller turns, said plates being each provided with a flange extending inwardly toward the middle of said rollers and positioned

between said casing and the ends of said rollers to prevent the goods from spreading materially beyond the ends of said rollers and resilient means also between said casing and the ends of said rollers to yieldingly engage the opposite edges of the goods passing between said rollers.

5. In a soap expressing device adapted for use in connection with an elongated soaping container having an opening, near the top thereof, through which the goods are placed in and are withdrawn from said container, of a driven roller mounted just below the upper edge of said opening and extending for the full length of said opening, means to drive said roller so that its upper surface moves away from said opening, a presser roller above and parallel to said first mentioned roller, and over which the operator may reach through said opening, to the interior of said container, and over which roller he may readily reach to the rear sides of said rollers to insert goods therebetween, bearings for the ends of said presser roller, each of said bearings being movable upwardly and downwardly, forwardly and rearwardly substantially independently of the bearing at the other end of said shaft to permit the said second roller to conform to any unevenness of the goods in passing between said rollers, a pedal operable by the operator standing in front of said rollers, and connections between said pedal and said bearings whereby a downward pressure by the operator on said pedal is operative to draw said presser roller into contact with the upper surface of goods passing over said driving roller, and yielding means pressing upwardly against the bearings of said presser roller to normally hold said presser roller above and spaced from said driven roller.

In witness whereof, I have hereunto set my hand this first day of April, 1929.

GEORGE WOELFEL.
